UNITED STATES PATENT OFFICE.

ALOYSIUS NIEMCZURA, OF AMSTERDAM, NEW YORK.

CALENDAR-CLOCK.

1,336,150.

Specification of Letters Patent. Patented Apr. 6, 1920.

Application filed January 2, 1918. Serial No. 203,986.

To all whom it may concern:

Be it known that I, ALOYSIUS NIEMCZURA, a citizen of the United States, resident of Amsterdam, county of Montgomery, and 5 State of New York, have invented certain new and useful Improvements in Calendar-Clocks, of which the following is a specification.

This invention relates to improvements in 10 calendar clocks, which indicate the year, the month of the year, the days of the month, the days of the week, the various phases of the moon, and if it be a leap year in addition to the function of the clock in indicating 15 time.

The object of the invention is to provide a neat appearing casing in which all of these several movements are operated and controlled by a standard clock movement, the 20 invention consisting in supplying a combination of novel means by which these objects are accomplished, and which are attained by the novel construction and combination of parts hereinafter described and 25 shown in the accompanying drawings, forming a material part of this specification, and in which:—

Figure 1 is a front elevational view, showing a clock made in accordance with the 30 invention.

Fig. 2 is an enlarged front elevational view of the clock movement as combined with the several actuating mechanisms for the calendar movements.

Fig. 3 is a front elevational and sectional view, taken on a vertical plane and indicating the several attachments, parts being broken away, in order to disclose the construction.

Figs. 4 and 5 are both front elevational views showing the Geneva stop and its co-operating parts.

Referring to Fig. 1 of the drawings, a casing 25, substantially rectangular in shape, is shown to rest upon a base 26, and has at 45 its upper front portion the usual clock face or dial 27 upon which are disclosed the numerals from 1 to 12, in the ordinary manner, time being indicated by the minute hand 28, and the hour hand 29.

Centrally below the clock dial is a transversely disposed rectangular opening 30 in which is disclosed numerals representing the year. To the left of this opening is a cir-

cular opening 31 through the transparent 5 covering of which is disclosed the words "Leap year" if such be the case, or a numeral representing the first, second and third year thereafter, these several characters being printed upon the outer surface of a disk 32 60 the actuation of which will be further on described.

Upon the opposite side of the opening 30, is a similar circular opening 33 in which is disclosed the various phases of the moon, 65 indicated upon a moving disk 34. Below the opening 30 is another longitudinal opening 35, through which the peripheral portions of two drums are disclosed, that at the left 36 indicating the several months, while 70 upon the right drum 38 are shown the several days of the week. Below this rectangular opening is a circular opening 40, at the center of which numerals representing the days of the month appear, the same 75 being imprinted upon the periphery of a rotatable disk 42, the several openings disclosing all of the various showings usually found upon a face of a calendar clock.

Pivoted to one of the depending elements 80 44, of the clock frame 45, is a lever 46, having a downturned arm 47, from which extends a lateral projection 48, having one flattened side adapted to make contact with the periphery of a scroll face cam 50, secured on the shaft 51, journaled in the sides of the clock frame 45, and which is rotated by a spur gear 52 by power transmitted from the clock work and at such speed as to rotate once during every twenty-four hours, thus 85 raising the lever 46, and permitting it to drop each day.

Adjustably engaged in an outstanding lug 54, of the lever 46, is a rod 55, having an angularly bent end pivotally engaged near 95 the free end of a lever 56, secured at its inner end upon a shaft 58.

Secured to the shaft 58 is the inner end of a flat spirally coiled spring 60, the opposite end being engaged with a post 61, the 100 effect of the spring being to normally maintain the lever 56, in a downward position and hold the pin 48, against the peripheral surface of the cam 50.

In order to prevent an abrupt drop of the 105 lever 56, as the pin 48 passes down the sharp decline of the cam, the outer, free end of the lever 56, has formed with it a segment 64,

having teeth 65, which mesh with a pinion 66, mounted on a shaft 67, journaled in the clock frame, and upon which is also secured a gear 68, the teeth of which mesh with a pinion 69, which operates a fan 70, the action of the fan being to cushion the descent of the lever 56.

Means for actuating the days of the week drum will now be considered. This drum 10 38 is mounted upon a shaft 75, journaled in supports extending out from the clock frame, the shaft having engaged at its outer right-hand end, a bevel gear 76, meshing with a mating gear 77, mounted on the outer 15 end of a shaft 78, extending horizontally outward from the clock frame and on which is secured a seven toothed ratchet 78. This ratchet is finally positioned and held against inadvertent motion by means of a roller 80, 20 carried on a lever 81, mounted on a post 82, and pressed against the ratchet by the coiled spring 83.

The ratchet 78, is operated by contact with a pin 85, extending from the free end 25 of the link 86, journaled by the screw 87, to the lower end of a lever 88, provision being made at the joint to prevent overaction of the link 86, relative to the lever 88, which is engaged with a shaft 90, pivoted 30 in the clock frame.

Movement is transmitted to the lever 88, by contact along the inclined or beveled surface 91, with a pin 92, fixed at the lower end of the segment 94, so that as the lever 56 35 is lowered, the ratchet 78, is turned one tooth thereby moving the drum so as to show one day after another.

Over operation of the lever 56, should it occur, is provided for by the straight lower 40 portion of the lever 88, against which the pin 92 may ride without actuating the lever.

The lever 88, is held against the pin by 45 the coiled tension spring 94, one end of which is engaged with a lug 95, secured upon the shaft 90, while the other end of the spring is similarly secured to the shaft 96, extending between parts of the frame. Thus actuation of the day-of-the-week drum is accomplished.

50 The mechanism for moving the disk or drum upon which the days of the month are shown will now be described. A ratchet 100, having 31 teeth and mounted upon a horizontal shaft 101, parallel with the face of the frame and substantially central thereof, is turned by reason of its teeth making contact with a pin 102, set in the end of a lever 108, pivoted by the screw 104, to the lever 56, the end of the lever being provided with means preventing over operation and which is drawn by the spring 106, so as to maintain the pin 102, in contact with the teeth. An arm 108, bears a pin 109, engaged with the teeth of the ratchet, the 55 arm being secured to a shaft 111, and so

engaged with the spring 110, as to maintain the pin in constant contact and to prevent retrograde movement.

Secured on the shaft 101, is a beveled gear 112, meshing with a mating gear 113, fixed 70 upon the upper end of a vertical shaft 114, upon the lower end of which is engaged a disk 42, bearing numerals upon its periphery from 1 to 31, indicative of the days of the month, while below this disk is a star 75 wheel 115, engageable with a roller 116, mounted upon the end of a bent arm 117, pivoted on a post 118, and held normally against the angular teeth of the star wheel 115, by the spring 119, the arrangement 80 being set so as to properly centralize the teeth so as to bring one of the numerals displayed upon the disk 42, directly into the center of the opening 40. Thus the disk 42, is moved from day to day whenever 85 the incline of the cam 50, permits the lever 46 to move downward.

Obviously, however, as all months do not contain 31 days, it is necessary to provide a compensating mechanism, whereby the 90 action of the lever 56, is modified. To this purpose there is set in the side of the lever 56, a pin 120, the same extending outward and normally engaging with the upper step 121, formed on the stop lever 122, having 95 other steps 123, and 124, on its right hand side and which is pivotally mounted upon a shaft 125 attached to which is another lever 126, the same being held toward the ratchet 100, by means of a coiled spring 128. The 100 lever 122, can be moved into such position that the contact pin 120, will engage with the steps or surfaces 121, 123 or 124, or drop below according to whether the month has 28, 29, 30 or 31 days.

105 This stop is moved by contact of the lower lever 126, with a pin 130, set in the end of a sliding bar 132, having a similar pin 133, set in its opposite end, engageable by the concave surface of a sliding cam 135, held 110 by the pivot 137, set in the upper end of an arm 138, pivotally engaged on the shaft 139, which arm is projected forward by a pin 140, set in the cam 135, the cam being given a rectilineal movement by reason of 115 an attached link 142, having a slot 143, movable on the shaft 144, on which is a flat plate 145, having an irregular peripheral edge designated respectively 146 and 147, the raised portions 147 representing months 120 having 30 days and which through the sliding bar 132, operates the lever 122, so that the pin 120 will strike upon the step 123, while ordinarily motion is transmitted by the peripheral portion 146 of the plate, it 125 being understood that the sliding bar 132, rotates with the ratchet 100.

Motion is transmitted to the shaft 144, by means of a twelve toothed ratchet 150, engageable with the teeth of which is a pin 130

151, fixed in the end of the link 152, its opposite end being pivotally engaged with a lever 160, carrying a pin 158, actuated by a cam 155, fixed on the shaft 101. The lever 5 160 is pivoted upon a stud 161, and held normally against the cam by action of the spring 162. The upper end of this lever 160 is provided with a segment 165 engaging with a pinion 166, mounted upon a shaft 10 167, and carrying a gear 168, engaged with a pinion 169 driving a fan 170, so that as the lever 160 is drawn toward the shaft 101 due to the pull of the spring 162, the rapid 15 decline of the cam 155, is lessened by the action of the fan.

The sliding bar 132, is held against the side of the ratchet 100 by means of the head 172, of a pin, the shank or stem of which operates in a slot 173, the opposite outer end 20 of the bar being pivotally connected by a link 174, pivoted by a screw 175, to the rim of the ratchet so that the bar 132 is free to oscillate, being held normally in place due to the spring 176, coiled about the screw 25 175, maintaining the pin 133, against the cam 135, during certain parts of the revolution of the ratchet 100, so that the pin 130, will actuate the lever 126. Thus the action of the rotatable plate 145 controls 30 the stop lever 122.

Months of 31 days corresponding with depressions 146 on the plate 145 actuate the mechanism so as to allow step 121 to be held in position to contact with the pin 120, 35 while months of 30 days, corresponding to the raised elevations 147, bring the step 123, into position to contact with the pin 120, while months of 29 days as February during leap year, corresponding to the raised tooth 40 178 move the stop lever so that the pin 120, will make contact with the step 124.

The Geneva stop 180 is held against over-operation by a spring actuated detent 181 and is rotated by a pin 182, set in the bar 45 186. In order to provide for action of the stop lever 122, as during February of ordinary years in which there are 28 days, the sliding tooth 185, engaged with bar 186, and carrying a pin 187, is adapted to engage 50 with the Geneva stop 180, the bar being pressed against the same by a lever 183, under the influence of a spring 184, when the plate 145 is at a certain point, the pin being engageable in one of the recesses 55 188, formed in the Geneva stop element 180, these recesses being in opposite sides, and as the Geneva stop is turned but once during the full revolution of the plate 145, obviously two of the eight spaces are deeper 60 recessed than the rest so that the movable tooth 185 will be actuated every fourth year and through it change the connection actuating the stop lever 122, so that the operating lever 56, will travel its full 65 limit with pin 120 resting on the stop 127.

Also mounted on the shaft 144, is a bevel gear 190, mating with a mating gear 191, fixed upon the shaft 192, mounted horizontally at the bottom of the casing in line with the shaft 75, and carrying the drum 36, 70 which obviously will be rotated from one month to another at the beginning thereof.

Also mounted upon the shaft 144, is a disk 195, having a cam like depression 196, with which is engageable the turned end 198, 75 of the bell crank lever arm 200, fulcrumed on a pin 201, the other arm 202, of the lever extending upward and having pivotally engaged by the screw 205, an arm 206, in which is engaged a pin 207, by means of 80 which is actuated a ratchet 208, secured on a shaft 210, upon which is also engaged the disk 32, bearing indications of the year, whether it be leap year, first, second or third year thereafter, the same showing 85 through the openings 31 in the front of the clock casing.

A detent 215, carries a roller held against the teeth of the ratchet by means of a spring 216. Thus when the lever arm 202 is actuated by means of the cam profile 196, under the influence of the spring 218, the disk is caused to rotate. Also engaged by the pivot screw 205, is an oppositely extending arm 220, having a pin 221, engageable with a 90 ratchet 222, mounted upon a shaft 224, upon which is secured a bevel gear 225, the ratchet being held against motion by means of a detent 227. The gear 225 meshes with a mating gear 228, secured upon a shaft 230, 100 which conveys motion to the first drum 232, bearing numerals from 0 to 9. Ordinary carrying connections engage between the first and second drum 233, so that when the first drum has made one complete revolution, the second drum has turned one point, the third drum 234 being fixed or stationary.

Actuation of the disk 34, a portion of which is opaque, or black and the remainder 110 orange colored to represent the moon, is accomplished as follows:—This disk is centered upon a shaft 240, to which is also secured a ratchet 241, held normally against rotation, by means of a detent 242, and actuated by a pin 245, held in the end of a link 246, pivoted on a screw 247, to a lever 248, having an extension 250, the outer end 251, of which is bent to make contact with the lever 56. Thus as the lever is operated once 115 each day, a similar rotary motion is transmitted to the disk 34, so that the various phases of the moon are correctly indicated.

In addition to the foregoing, if for any reason the clock becomes stopped and it is necessary to adjust the days of the week in accordance, this can be readily accomplished by operating the extending handle 255, secured to the shaft 73, in an obvious manner.

It is believed that from the foregoing 120

that a complete disclosure of the invention has been made and which will enable any one skilled in the art to construct and operate a clock in accordance with the invention, 5 therefore:—

Having thus described and shown the several instrumentalities of the invention, what I claim as new and desire to secure by Letters Patent, is:—

10 1. In a calendar clock of the character described, the combination of a clock mechanism with a lever adapted to be dropped once every twenty-four hours, of a second lever, a rod connecting both levers, a spring 15 for normally maintaining the second lever in a downward position, a toothed segment on the end of the second lever, a pinion in mesh with said segment, and a fan operated by said pinion for cushioning the de- 20 scent of said second lever, substantially as described, and for the purpose set forth.

2. In a calendar clock of the character described, the combination of a clock mechanism with a lever adapted to be dropped once every twenty-four hours, of a second 25 lever connected with the first named one, a week drum, a shaft on which said drum is mounted, an operating lever for said drum, and means for connecting said operating

lever with said secondly named lever, means 30 for preventing overaction of the latter lever, and means for operatively connecting said drum shaft with said operating lever, substantially as described.

3. In a calendar clock of the character de- 35 scribed, the combination of a clock mechanism with a Geneva stop provided with eight spaces including two deeper than the others, a sliding bar, a flat plate having an irregular peripheral edge, a sliding tooth adapted 40 to engage with said Geneva stop at a certain position of said plate, and adapted to enter the two deeper recesses of said Geneva stop every fourth year.

4. In a calendar clock of the character de- 45 scribed, the combination of a clock mechanism with a disk bearing the inscriptions leap year, first, second or third year there- 50 after, of a shaft, a disk having a cam depression mounted on said shaft, a bell crank lever having one arm engaging with said depression, a ratchet adapted to be operated by the other arm of said bell-crank lever for operating said disk, and a roller held against the teeth of said ratchet.

In testimony whereof I have affixed my signature.

ALOYSIUS NIEMCZURA.
